United States Patent Office

Des. 175,122
Patented July 12, 1955

175,122

DISPLAY CONTAINER OR SIMILAR ARTICLE

Herbert W. Marano, Summit, N. J., assignor to Wilson Jones Company, Chicago, Ill., a corporation of Massachusetts

Application March 10, 1955, Serial No. 34,981

Term of patent 14 years

(Cl. D80—5)

Figure 1 is a front perspective view of a display container or similar article showing my new design with the cover open and the container rearwardly inclined;

Figure 2 is a perspective view with the cover open and the container in a vertical position;

I claim:

The ornamental design for a display container or similar article, as shown.
